VAPOR FUEL INJECTOR FLAMEHOLDER
William C. Colley, Jr., West Chester, Ohio, assignor to
General Electric Company, a corporation of New York
Filed Aug. 27, 1962, Ser. No. 219,695
8 Claims. (Cl. 60—39.72)

The present invention relates to a vapor fuel injector flameholder and, more particularly, to a combination gaseous injector and flameholder for high inlet temperature ram burners and turbojet augmentors.

In ramjet and turbojet engines designed to operate at high supersonic flight speeds, the temperature of the air entering the ram burner or augmentor may exceed 2000° F. As such temperatures approach the melting point of most commonly used structural materials, any objects placed in this air stream must either be very heavily constructed, or must be cooled by external means. When such engines are required to operate over a wide range of flight speeds, it is necessary to mount flameholders within the burner as is done in present day engines. A convenient and well-known method of cooling these flameholders is to pass through them the fuel ultimately consumed in the burner.

It is anticipated that the fuel to be used in these high speed engines will be in a gaseous state at the time of use. It may be a fuel which is a gas at normal temperatures, such as hydrogen or methane, and which is stored aboard the aircraft as an extremely cold liquid in insulated tanks, or it may be a fuel which is normally a liquid, such as highly refined kerosene or a pure liquid hydrocarbon compound. In either case, the fuel will be employed to cool many parts of the engine and airframe, and in so doing will be heated to the extent that it will be in gaseous form when delivered to the burner. Thus, the fuel will be burned as a vapor.

It is further desired to burn as close to stoichiometric as possible. This, as is well known, is the chemically correct mixture of fuel and air which provides just enough fuel to theoretically consume all the oxygen in the air and no more. The stoichiometric mixture varies for different fuels and this mixture approximately corresponds to the highest temperature mixture obtainable or, in other words, the hottest flame obtainable which therefore provides the most energy release. Such a desired mixture encounters the standard problem, whether in aircraft or other internal combustion engines, of uniform fuel distribution. In a reaction engine, this requires a most uniformly distributed fuel across the entire area of the burner. This provides the highest efficiency obtainable and a close approach to the stoichiometric mixture. In addition, this must be done in an extremely fast moving fluid stream.

It is known to use V-gutters and inject fuel in various ways in the vicinity of the V-gutter. The V-gutter provides a stagnant or dwell region for burning to initiate and/or occur. It is further known to use fuel injection tubes which contain orifices injecting the fuel at right angles to the air stream and various types of these injectors have been successfully built. One of the problems encountered is that the fuel jets at very high fuel flows penetrate so completely into the air stream that they leave the region next to the V-gutter with very little fuel. Since the V-gutter's purpose is flameholding, obviously it is necessary to have fuel in the vicinity of the V-gutter if it is to function. It is common to put additional orifices in the tubes to inject fuel in the direction of the air flow. It has been found that injecting fuel at high fuel pressure downstream into the V-gutter wake causes the fuel to penetrate the recirculation zone of the flameholder too rapidly to burn. It has also been suggested that fuel be dribbled down the side of the V-gutter plates so that it will stay in

2

the immediate vicinity. By itself, this does not give uniform distribution since there is no penetration of the fuel into the main flow of the air stream.

The main object of the present invention is to provide a fuel cooled vapor fuel injector flameholder that is operable over a wide range of fuel air ratios and the optimum fuel distribution is automatically attained at all fuel flows.

A further object is to provide such an injector flameholder which combines both normal or transverse injection and upstream injection in such a way as to provide uniform fuel distribution.

A further object is to provide deflectors in conjunction with the upstream injection to cooperate with the transverse injection and provide the uniform fuel distribution.

Briefly stated, the invention provides a vapor fuel injector flameholder for a combustion chamber which uses a hollow tube closed upon itself and conducting vapor fuel. The tube is disposed across the combustion chamber and has a pair of plates secured to it and extending downstream to form a V-gutter flameholder. A series of diametrically opposed spaced apertures in the tube direct fuel transversely of the combustion chamber and a second series of spaced apertures in the tube direct fuel upstream and substantially at right angles to the first series. A deflector is placed over each of the second series of apertures and the deflector is spaced from the tube to intercept the emerging fuel flow and direct the flow as a film along the V-gutter plates.

While the specification concludes with claims particularly pointing out and distinctly claiming the subject matter which is regarded as the invention, it is believed the invention will be better understood from the following description taken in connection with the accompanying drawing in which:

FIGURE 1 is a partial cross-sectional view of a typical spaced ring fuel injector as used in an afterburner,

FIGURE 2 is an end view of FIGURE 1,

FIGURE 3 is a partial cross-sectional view of the invented injector flameholder, and

FIGURE 4 is a partial side view of the flameholder showing the spaced deflectors.

Referring first to FIGURE 1, there is shown a partial cross-section of a reaction engine having a casing 10 forming a combustion chamber which, as shown, may be an afterburner or augmentor section 11 and an inner cone 12 guiding the motive fluid or exhaust gases downstream from a turbine not shown. Further combustion may take place in section 11 and to this end there is provided a fuel injector flameholder arrangement generally indicated at 13 which is disposed transversely across the combustion section 11. The injector flameholder 13 may comprise a series of concentric tubes 14 that are supported by hollow struts such that struts and tubes may convey fuel for injection into section 11. Tubes 14 may be arrangements other than concentric tubes but this arrangement is preferable. The fuel normally will be vaporized, having been used elsewhere as a cooling medium and having been vaporized in the process.

The individual vapor injector flameholder is shown in detail in FIGURE 3. In order to provide a stagnant region and flameholding capability, tube 14 has a pair of flat spaced plates 15 extending downstream from the tube to form a V-gutter flameholder. The plates normally diverge as shown an amount dependent on the particular environment in which they are to be used. As is well known, a recirculation zone 16 is formed at the downstream end of the plates at which a pilot flame may dwell due to the stagnant condition in the recirculation zone. It is desired to obtain uniform fuel injection across section 11 and to this end tube 14 is provided with a first series of diametrically opposed apertures 17 which are axially spaced along the tube as shown in FIGURE 4. These

apertures are used to inject the fuel transversely to the combustion chamber as shown by the arrow in FIGURE 3 and this form of injection is known. At high fuel pressures the penetration of the transverse streams from apertures 17 leave the area adjacent the flameholder starved of fuel. A plurality of the concentric tubes 14, arranged as shown in FIGURES 1 and 2, provide a transverse blanket of fuel across section 11, but, in the immediate vicinity of the flameholder, without more, the fuel supply is inadequate and the flameholder does not function. To cure this, a second series of spaced apertures 18 is provided in the tube and directed upstream of the tube as shown in FIGURE 3. It is to be noted that this aperture 18 alone, injecting fuel upstream, would penetrate some distance upstream and then mix with the approaching air and, being slightly diluted by that air, it would be carried back on the flameholder and would not be as effective as if it had been held in the vicinity of the injector in the first place. In other words, the fuel-air ratio would tend to decrease providing an insufficient burning mixture adjacent the flameholder.

The present invention includes a means for holding the fuel in the vicinity of the injector and this is done by providing a spaced deflector member 19 which may be secured by strap 20 to the tube as shown in FIGURE 4. The purpose of the deflector is to hold the vapor fuel exiting from aperture 18 in the immediate vicinity of the injector and thus allow it to flow down the side of the flameholder plates as a sheet or film as shown by the arrows in FIGURE 3. Preferably, a single aperture 18 is shown centrally disposed so that the fuel will split upon hitting the top and flow down both sides and thus lose most of the injection energy in the process. This is desired since it is necessary to let the fuel flow as a film along the plates. Furthermore, the use of the fuel striking the inner surface of deflector 19 serves at the same time to cool it so that it does not burn away. For best results, it has been found that the spacing of the deflector from the tube or the radial distance 21 should be a maximum of one-fourth the diameter of the tube if a cylindrical tube is used or substantially one-fourth the width of the tube if other than a cylindrical tube is used. Larger spacing results in insufficient cooling of the deflector by the fuel. Additionally, with a larger space, air circulates back under the deflector permitting unwanted combustion between the deflector and tube. Furthermore, the deflector 19 preferably extends around the tube approximately the width of the tube as shown in FIGURE 3. In the preferred concentric arrangement shown this width or projected area is substantially the diameter of the tube. Wider than that or overhanging would tend to expose more of the deflector to the hot gases in section 11 and place part of the deflector farther away from the relatively cool jet of fuel through aperture 18 to lower the cooling effectiveness of the fuel in the overhanging portion of the deflector. Additionally, it is unneeded hardware adding additional structure and weight.

Referring next to FIGURE 4, it can be seen that the deflector 19 is spaced from an adjacent similar deflector, there being a plurality of deflectors around the tube 14. It has been found that this spacing between adjacent deflectors should not exceed the tube 14 diameter. The spacing between deflectors is required since the fuel from apertures 17 has a tendency to pick up the low velocity flow from apertures 18 and to carry both fuels out into the main stream. This tendency is avoided by providing gaps between deflectors to remove the aperture 17 fuel from the low velocity fuel dribbling as a film down the plates 15. The maximum spacing is desired as a limit in order to avoid getting too far from the transverse fuel apertures 17 and thus moving the flameholding portion of plate 15 too far away from the fuel issuing from apertures 17.

Additionally, deflectors 19 have an axial length with a maximum equal to the tube diameter. This is the axial length along the deflector as shown in FIGURE 4. Greater than the maximum, parts of the deflector get too

far away from aperture 18 for adequate deflecting, cooling, and distributing of the fuel. The spaced deflectors are preferred over a continuous deflector for the same reason in that portions of the continuous deflector would be too far from the high velocity jet from aperture 18 resulting in poor distribution and inadequate cooling. Consequently, the spaced deflector arrangement is a better combustion arrangement for more efficient burning.

Preferably, to avoid spillage of fuel from aperture 18 into the side region between deflectors and consequent reduction of the film of pilot fuel down plates 15, each deflector is provided with end plates 22 (which may be a continuation of, or part of, straps 20) confining the fuel to the underside of the deflectors.

With the arrangement just described, it will be apparent that at low fuel flows the penetration of fuel from apertures 17 is slight and the two fuel streams, from apertures 17 and the film from apertures 18, merge to concentrate the fuel in the vicinity of the flameholder. At high fuel flows, the jets of fuel from apertures 17 penetrate transversely well into the air stream to create a nearly uniform fuel distribution while the fuel from apertures 18 flows directly into the wake of the flameholder thus insuring the maintenance of a combustible mixture in this region at all times. The ratio of the amount of fuel injected through apertures 17 to that through apertures 18 is regulated by the number and size of the respective apertures. This ratio will normally vary with the fuel employed, the operating conditions being encountered, and the physical arrangement of the flameholders within a particular burner.

Cooling is provided by passing the fuel directly through the flameholder before burning and thus lighter construction may be used. Fuel is injected in such a manner that the optimum fuel distribution is automatically obtained at all burner fuel air ratios, yet flame-out due to overpenetration of the fuel jets is avoided. Further, the flameholder contains its own fuel manifold thus simplifying the structure and obviating the need for manifolding external to the combustion section.

While there has hereinbefore been described a preferred form of the invention, obviously many modifications and variations of the present invention are possible in the light of the above teachings. It is therefore to be understood that within the scope of the appended claims, the invention may be practiced otherwise than as specifically described.

I claim:

1. A vapor fuel injector-flameholder for a reaction engine combustion chamber comprising, a hollow tube for conducting vapor fuel and disposed across the combustion chamber, a pair of plates secured to and extending downstream from the tube to form a V-gutter flameholder, said tube having a first series of diametrically opposed spaced apertures for directing fuel transversely of the combustion chamber, a second series of spaced apertures in said tube directed upstream thereof, and a deflector over each of said second series of apertures, said deflector being spaced from said tube and conforming in curvature therewith to direct fuel from said second apertures as a film along said plates.

2. Apparatus as described in claim 1 wherein said deflectors are spaced from said tube a maximum of one fourth the width of said tube.

3. Apparatus as described in claim 1 wherein said deflectors extend over said second series of apertures the projected width of said tubes.

4. Apparatus as described in claim 1 wherein said hollow tube is cylindrical and said deflectors are spaced from said tube a maximum of one fourth said tube diameter.

5. Apparatus as described in claim 4 wherein said deflectors have a maximum length along said tube equal to said tube diameter.

6. A vapor fuel injector-flameholder for a reaction engine combustion chamber comprising,
- a hollow vapor fuel conducting cylindrical tube closed in a circle upon itself and disposed transversely across the combustion chamber,
- a pair of flat spaced diverging plates secured to said tube to form therewith a V-gutter flameholder with rounded upstream apex,
- said tube having a series of diametrically opposed spaced apertures for directing fuel transversely of the combustion chamber,
- a second series of spaced apertures in said tube directed upstream thereof,
- a deflector over each of said second series of apertures spaced from said tube and concentric therewith,
- said deflector covering the width of said tube to intercept fuel flow from said apertures and direct it as a film along said plates.

7. Apparatus as described in claim 6 wherein each of

said deflectors has an end plate to prevent spillage over the end of the deflectors.

8. Apparatus as described in claim 6 wherein each of said deflectors is spaced from said tube a maximum of one fourth the diameter of said tube and is provided with an end plate to prevent fuel spillage over the end of the deflectors.
